DESIGN FOR A LICENSE PLATE FRAME OR SIMILAR ARTICLE

Benjamin Lapidus, Brooklyn, N. Y.

Application March 25, 1939, Serial No. 83,826

Term of patent 7 years

To all whom it may concern:

Be it known that I, Benjamin Lapidus, a citizen of the United States and resident of Brooklyn, in the county of Kings and State of New York, have invented a new, original, and ornamental Design for a License Plate Frame or Similar Article, of which the following is a specification, reference being had to the accompanying drawing, forming part thereof, in which,

Fig. 1 is a front elevational view of a license plate frame embodying my new design.

Fig. 2 is a cross sectional view thereof taken substantially on the line 2—2 of Fig. 1.

Fig. 3 is a top plan view thereof, and

Fig. 4 is a rear elevational view thereof.

The design is characterized by two identical,

symmetrical U-shaped members between which are interposed two identical connectors. Said connectors comprise a central collar of larger external transverse contour than the external transverse contour of said U-shaped members, and end collars abutting the ends of said U-shaped members. The end collars have an external transverse contour identical to the external transverse contour of said U-shaped members.

I claim:

The ornamental design for a license plate frame or similar article, substantially as shown and described.

BENJAMIN LAPIDUS.
